UNITED STATES PATENT OFFICE.

JAMES SHEARER, OF JOHANNESBURG, TRANSVAAL, SOUTH AFRICA

RECIPROCATING ENGINE.

Application filed December 31, 1924, Serial No. 759,191, and in the Union of South Africa November 12, 1924.

This invention relates to reciprocating engines and particularly internal combustion engines and compressors and its object is to increase the efficiency of such machines.

According to this invention a cylinder open at both ends carries two pistons between which the explosive mixture or, in the case of an air compressor, air, is introduced, each piston being connected by means of a connecting rod to a crank shaft. This enables the explosion to take place when the crank of one of the crank shafts is at its most suitable position for receiving the driving impulse, namely, at or near the position when the crank makes an angle of 90° with the connecting rod. This is impossible with the ordinary cylinder which is closed at one end.

The invention is illustrated in the accompanying drawings.

Figs. I and II show diagrammatic view of the cylinder and piston at two separate points in the cycle.

Fig. III shows one example of a valve action.

1 represents a cylinder open at both ends and 2 and 3 are two pistons working therein. Piston 2 is connected to a crank 4 by a connecting rod 5 and piston 3 is connected to a crank 7 by a connecting rod 6.

The two cranks 4 and 7 are geared together by gear wheels as indicated at 11, 8, 9 and 10.

Fig. I shows the engine on the point of firing, gas having been introduced between the pistons 2 and 3 and compressed in the usual way. It will be seen that the effect of the explosion is transmitted to the crank 4 when the said crank is at or about its most effective position for receiving the driving impulse of the piston 2. The cranks revolve in the direction shown by the arrows in Fig. I.

Fig. II shows the position of the cranks, 4 and 7 after the firing and exhaust and suction strokes are completed the cranks having turned through 470°. The engine is now at the end of the suction stroke. The charge is then compressed while the engine again arrives at the position shown in Fig. I.

It will be seen that the firing and exhaust strokes occupy one revolution and the suction and compression strokes likewise occupy one revolution. The engine therefore gives one explosion for every two revolutions of the crank s. ft.

Fig. III shows in diagrammatic form one example of an engine constructed according to the invention.

Eccentrics 12 and 13 are mounted respectively on the gear wheel shafts 9 and 8 and carry rods 14 and 15 which actuate exhaust valve 20 and inlet valve 19 through rockers 18 and 17.

The invention is not limited to the particular example of valve gear shown; any suitable valve gear may be employed, the invention residing in the use of two pistons in an open ended cylinder as indicated.

I claim:

In a reciprocating engine, two pistons adapted to reciprocate in opposite directions, a space between the said pistons, an open ended cylinder in which said pistons work, two crank shafts to which the pistons are respectively connected, means to prevent relative movement between the crank shafts, the arrangement being such that one of the cranks is approximately at right angles to its connecting rod when the two pistons are nearest to each other.

In testimony whereof I affix my signature.

JAMES SHEARER.
